A. Annan,
Knife Sharpener.
No 22,055. Patented Nov. 16, 1858.

UNITED STATES PATENT OFFICE.

ALEX. ANNAN, OF NEW YORK, N. Y.

KNIFE-SHARPENER.

Specification of Letters Patent No. 22,055, dated November 16, 1858.

To all whom it may concern:

Be it known that I, A. ANNAN, of the city, county, and State of New York, have invented a new and Improved Knife-Sharpenering Device; and I do hereby declare that the following is a full, clear, and exact description of the same, reference being had to the annexed drawings, making a part of this specification, in which—

10 Figure 1, is a longitudinal vertical section of my invention, the plane of section passing through the center. Fig. 2, is a plan or top view of ditto. Fig. 3, is a detached end view of the cutters. Fig. 4, is a detached perspective view of ditto.

Similar letters of reference indicate corresponding parts in the several figures.

This invention consists in having two cutters formed of rectangular steel plates cut or 20 corrugated at their sides, similar to files, and fitted in oblique grooves in a metallic frame, the cutters being placed in such position that they retain each other in the frame and are rendered capable of being adjusted in varying 25 positions in the plane of their movement so that the whole surface of the plates may be used as cutting surfaces.

To enable those skilled in the art to fully understand and construct my invention, I 30 will proceed to describe it.

A, represents a cast metal base having two upright plates B, B, attached to it, one at each side, the base between the uprights being slotted or having an opening a, formed 35 in it. Each upright plate B, has a V-shaped slot b, formed in it, and each plate also has two grooves c, c, made in it, the grooves being in oblique or inclined positions, parallel with the edges of the slots b, see Fig. 1.

40 C, C, represent rectangular steel plates, the ends of which are beveled so as to fit in the grooves c, c, in the plates B, the plates being allowed to slide freely up and down

therein. The plates C, C, when fitted in the grooves c, c, are inclined or beveled, and 45 have such a relation to each other that their lower ends will touch or be in contact, and thereby retain one another between the plates. This will be clearly understood by referring to Figs. 1 and 3, and it will be seen 50 that in consequence of the oblique or V-shaped position of the plates B, one plate may be elevated above or below the other and be retained equally as well as when their lower ends are in contact, see Fig. 1. 55

The knife to be sharpened has its blade, which is shown in red, drawn between the two plates C, C, which cut each side of its lower edge and form basils, bringing said lower edge to a cutting edge. As the plates 60 become worn, they may be shifted one relatively with the other, so that the whole surface of each plate may be used. The plates may be cut or corrugated on both sides, so that when one side is worn, the plates may 65 be turned and the opposite sides used. The plates may have recesses or grooves d, made in them at their lower ends to permit the shavings to pass out, see Fig. 4.

I do not claim the employment or use of 70 corrugated steel plates C, for cutters, for such have been previously used for knife and scissor sharpeners, but

Having thus described my invention, what I claim as new and desire to secure by Letters Patent, is,

The two cutter plates C, C, with cut or corrugated surfaces, placed in oblique positions relatively with each other, and arranged or fitted between the upright plates 80 B, B, of a base A, substantially as and for the purpose set forth.

ALEXANDER ANNAN.
